(57) **CLAIM**

The ornamental design for a pasta, as shown and described.

DESCRIPTION

FIG. 1 is a front, top and left side perspective view of a first embodiment of a pasta, showing my new design;

FIG. 2 is a top plan view thereof;

FIG. 3 is a right side elevation view thereof, the left side elevation view being a mirrored image thereof;

FIG. 4 is a front elevation view, the rear elevation view being a mirrored image thereof;

FIG. 5 is a front, top and left side perspective view of a second embodiment of a pasta, showing my new design;

FIG. 6 is a top plan view thereof;

FIG. 7 is a right side elevation view thereof, the left side elevation view being a mirrored image thereof; and,

FIG. 8 is a front elevation view, the rear elevation view being a mirrored image thereof.

The broken lines shown in FIGS. 1, 3–5 and 7–8 illustrate portions of the pasta, that form no part of the claimed design.
